UNITED STATES PATENT OFFICE

RICHARD V. UHRIG, OF LOS ANGELES, CALIFORNIA

SLIP FOR ROTARY TABLES AND SPIDERS FOR HANDLING PIPE

Application filed July 2, 1928. Serial No. 289,736.

This invention has to do with a slip for use in a rotary table, or the like, and it is a primary object of the invention to provide a slip that is easily handled and which cannot 5 fall into the well.

In the drilling of wells with the rotary method, it is common to use slips in connection with rotary tables, or the like, for the purpose of holding or engaging parts such as 10 tubing, casings, etc. These slips are segmental wedge members and, in accordance with the usual construction, there are three or more in each set. The slips are usually handled separately or individually, and it is common 15 to provide each slip with a handle either in the form of a U-shaped metal bale or in the form of a strap of flexible cable, or the like. In practice, difficulty is sometimes experienced in handling a slip as the ordinary form 20 of handle just mentioned does not enable an operator to engage the slip conveniently with more than one hand. Further, serious trouble is often caused by a slip being accidentally released to fall through the rotary table 25 and into the well, it being necessary in such case to fish the slip out of the well, which operation is usually very difficult.

It is an object of my present invention to provide a slip having a handle whereby it 30 can be easily and conveniently handled. The handle provided by this invention is such as to enable an operator to conveniently grip it with both hands.

It is another object of the invention to 35 provide a slip which cannot be passed or lost through a rotary table, that is through the opening in which it operates.

It is a further object of the invention to 40 provide a slip suitable for use in a spider as well as a rotary table.

The various objects and features of my invention will be best and more fully understood from the following detailed description of a typical form and application of the 45 invention, throughout which description I refer to the accompanying drawings, in which:

Fig. 1 is a plan view of a rotary table showing slips provided by this invention in operating position thereon. Fig. 2 is an ex-

terior or outside view of the slip showing the handle in an up or extended position. Fig. 3 is a plan or top view of the slip showing the handle lowered or in a horizontal position, and Fig. 4 is a detailed sectional view 55 taken as indicated by line 4—4 on Fig. 3.

The present invention is particularly useful as applied to or in connection with slips such as are used in the usual form of rotary table of a rotary well drilling outfit. I have 60 therefore shown a typical rotary table 10 having the usual opening 11 to carry bushings, or the like. In the drawings I have shown slip bushings 12 in the opening of the table and have shown slips 13 embodying the present 65 invention in position in the bushings 12 to hold a casing C. In the particular case illustrated I have shown a set of casing slips embodying three individual or independently 70 movable slips. It is to be understood, of course, that the invention can be applied to slips of various sizes and shapes, a set of three slips having been shown merely for purpose of example.

Each slip 13 embodying the present invention comprises a main part or slip body 14 and a handle 15. The slip body may, as far as this invention is concerned, be of any suitable form of construction, the present invention being concerned primarily with the handle and the combination of the body and handle. In the drawings I have shown a common and popular type of slip in which the body is provided with a detachable inner 80 face 16 to engage a casing, or the like. The outer portion or exterior 17 of the body is made to seat or bear in the opening of the bushing 12.

The handle 15 provided by this invention is attached to the upper end portion of the slip body 14 and has a projecting part extending laterally beyond the body. In the preferred form of the invention illustrated in the drawings the handle comprises spaced legs 20 attached to the upper end of the slip body and extending a substantial distance therefrom, a transverse or laterally-disposed head 21 projecting in either direction beyond the legs, and connecting parts or extensions 22 of the legs 20 joining the outer ends of the 100

legs with the head 21. The legs 20 are attached to spaced points on the upper end of the slip body 14 and may extend in parallel relation from the body as clearly shown in the drawings.

5 The head 21 is disposed transversely or at right angles to the legs 20 and is made sufficiently wide to extend beyond the legs so that it is wider than the slip body. In practice the width or extent of the head 21 is made considerably greater than the smallest diameter of the opening in the bushing 12 so that the handle cannot possibly pass through the bushing. It will be obvious that 10 the length of the slip body and the combination of the slip body and handle make it impossible for the slip to be passed through the bushing 12 in a tilted position or sideways.

15 20 The handle may be formed so that the legs 20 are outwardly divergent or shaped so that their outer ends connect directly with the outer ends of the head 21. In the form of the invention illustrated the legs are parallel, and therefore outwardly curved extensions 22 are provided to connect the outer ends of the legs 20 with the ends of the head 21. In practice it is preferred to form the entire handle of a single bar or strap of metal, 25 30 it being obvious from the drawings how the handle can be easily bent or forged from plain bar stock.

It is desirable to provide a flexible, for instance pivotal connection, between the handle 35 and slip body. In the drawings I have shown lugs 30 provided on the upper end portion of the slip body and have shown a pivot pin 31 passing through the lugs 30 and through eyes 32 in the legs 20 of the handle to pivotally connect the legs with the slip body.

40 From the foregoing description it will be apparent that my invention provides a slip with a handle that can be conveniently and effectively gripped. The head portion 21 of 45 the handle is of such extent and is so disposed as to give an operator a very convenient purchase on the slip. The handle being proportioned to project laterally from either side, or beyond, the body of the slip, positively prevents the slip from being lost through 50 the opening in the slip bushing 12. The combination of handle and slip provided by this invention forms a structure that cannot be worked or manipulated in any way to pass 55 through the bushing opening, this being true even after the slip body has been materially worn.

Having described only a typical preferred 60 form of my invention, I do not wish to limit myself to the specific details set forth, but wish to reserve to myself any changes or variations that may appear to those skilled in the art or fall within the scope of the following claims.

65 Having described my invention, I claim:

1. A slip to operate in an opening in a rotary table including, a body to fit in the opening, and a handle on the body, the handle having a portion wider than the opening.

2. A slip for use in a rotary table having 70 an opening including, a body to fit in the opening of the table, and a handle on the body having a head part wider than the opening.

3. A slip to operate in an opening in a 75 rotary table including, a body to extend into the opening, and a handle on the body having a portion projecting in opposite directions laterally beyond the body so that it is wider than the opening.

4. A slip to operate in an opening in a rotary table including, a body to operate in the opening, and a handle on the body including legs attached to the body and projecting therefrom, and a head on the outer 80 ends of the legs, the head being substantially wider than the body and the opening.

5. A slip to operate in an opening in a rotary table including a body to operate in the opening, and a handle on the body including, legs pivotally connected to the body and extending in parallel relation therefrom, and a head carried by the outer ends of the legs transversely thereof, the head being wider than the body and wider than the opening. 95

In witness that I claim the foregoing I have hereunto subscribed my name this 5th day of June, 1928.
